SECTIONALIZING CIRCUIT BREAKER

Carl E. Mosley, Overland, Mo., and Kenneth R. Brown, Des Moines, Iowa, assignors to W. N. Matthews Corporation, St. Louis, Mo., a corporation of Missouri

Application May 8, 1948, Serial No. 25,924

8 Claims. (Cl. 200—108)

1

This invention relates to circuit breakers, and more particularly to sectionalizing circuit breakers for isolating a permanently faulted branch line of a power distribution system from the remainder of the system.

Among the several objects of the invention may be noted the provision of an automatic sectionalizing circuit breaker for use in a branch line of a power distribution system and in association with an automatic circuit recloser in the main line of the system for isolating the branch line from the main line upon the occurrence of a fault of substantial duration in the branch line; the provision of a circuit breaker of the class described adapted automatically to lock out and permanently to open the branch line in response to a sustained overload condition caused by a permanent fault in the branch line, but to remain closed upon the occurrence of momentary overload conditions caused by temporary faults in the branch line; the provision of a current-relay-controlled circuit breaker of this class adapted for trouble-free operation even though subject to extreme overloads; and the provision of a circuit breaker such as described which is economical to manufacture and reliable in operation in exposed locations. Other objects will be in part apparent and in part pointed out hereinafter.

The invention accordingly comprises the elements and combinations of elements, features of construction, and arrangements of parts which will be exemplified in the structures hereinafter described and the scope of the application of which will be indicated in the following claims.

In the accompanying drawings, in which one of various possible embodiments of the invention is illustrated,

Fig. 1 is a view in side elevation of a circuit breaker of this invention shown in solid lines in closed-circuit position;

Fig. 2 is a fragmentary plan view showing a control mechanism of the circuit breaker;

Fig. 3 is an enlarged vertical section taken substantially on line 3—3 of Fig. 2;

Fig. 4 is an enlarged vertical section taken substantially on line 4—4 of Fig. 2;

Fig. 5 is a vertical section taken on line 5—5 of Fig. 3, parts being broken away; and,

Fig. 6 is a schematic wiring diagram.

Similar reference characters indicate corresponding parts throughout the several views of the drawings.

Referring to the drawings, particularly to Fig. 1, the circuit breaker of this invention, generally

2

designated 1, comprises a mounting base or arm 3 adapted to be bolted in vertical position upon a cross arm or any other suitable support. Arm 3 is a conductor so as to be connectible to neutral or ground. Insulators 5 and 7 extend horizontally from the upper and lower ends of the arm 3, respectively. The upper insulator 5 is clamped at one end in a split ring clamp 9 carried by the upper end of the mounting arm 3. The lower insulator 7 is clamped at one end in a split ring clamp 11 carried by the lower end of the mounting arm 3.

The upper half 13 of the upper clamp 9 carries a grounding electrode 15. Supported by a clamp 15 around the middle waist portion of the insulator 5 is an intermediate electrode 19. At the outer end of the upper insulator 5 is a split ring clamp 21, the upper half of which supports a third electrode 25. The electrodes 15, 19 and 25 form in series two surge gaps for lightning arresting purposes. They ground transient high-voltage surges of current due to lightning or the like. The surge current is carried off through the mounting arm 3 to ground.

Similarly, the lower half 10 of the lower clamp 11 carries a grounding electrode 27. Supported by a clamp 29 around the middle waist portion of the lower insulator 7 is an intermediate electrode 31. At the outer end of the lower insulator 7 is a split ring clamp 33, the lower half 35 of which supports a third electrode 37. The electrodes 27, 31 and 37 form in series two surge gaps for lightning arresting purposes. They ground transient high-voltage surges of current due to lightning or the like, the surge current being carried off through clamp 11 to ground. The lower half 10 of the clamp 11 is provided with a terminal 39 for connection of a ground wire.

The split ring clamp 21 at the outer end of the upper insulator 5 comprises upper and lower jaws 41 and 43, respectively, held in clamping relation around the outer end of the upper insulator 5 by means of clamping bolts 45. The electrode 25 is fixed in the upper jaw 41. The lower jaw 43 is formed with extensions 47 in one of which is a feed line wire connector 49 (Fig. 2). The lower jaw 43 is formed with a horizontal bracket 51 having a bifurcated end portion 53. A platform 55 of insulating material is fixed upon bracket 51 by means of screws 57 and 59 extending through the platform into the legs of the bifurcated end portion 53 of the bracket. The lower jaw 43 (including bracket 51) is an elec-

trical conductor for conduction of current from connector 49.

The clamp 33 at the outer end of the lower insulator 7 comprises the lower jaw 35 which carries electrode 37 and upper jaw 61. These jaws are held in clamping relation around the outer end of the lower insulator by means of bolts 63. The lower jaw 35 of the clamp, which is an electrical conductor has an extension 65 for a line wire connector 67. The upper jaw 61 of clamp 33 is formed with a pair of spaced lugs 69 for the pivotal mounting of a movable switch member generally designated 71. The latter comprises a hinge member 73 pivoted at 75 between the lugs 69. A switch bar 77 extends upward from hinge member 73. The switch bar is encased in an insulating tube 79, composed of a suitable material such as fiber. This makes it safe if inadvertently touched. Hinge member 73 is provided with a hook 81 for application of a lineman's stick for switch reclosing purposes. A pigtail shunt from hinge member 73 around the pivot to the upper jaw 61 of clamp 33 is shown at 83. A coil spring 85 biases switch member 71 toward the mounting arm 3 to its open-circuit position. At the upper end of switch bar 77 is a generally U-shaped terminal 87 for cooperation with a latch member 89 carried by the platform 55.

The switch bar 77 is latched in circuit-closing position by latch member 89, the latter having below the platform a hooked portion 91 engageable in notch 93 in the U-shaped terminal 87 to hold the switch bar 77 in vertical position against the bias of spring 85. When latch member 89 is actuated to release the switch bar, the latter swings toward mounting arm 3 under the bias of spring 85 until its terminal 87 engages a lug 95 struck out from the mounting arm 3, as illustrated in dotted lines in Fig. 1. Latch member 89 is pivoted at 97 in a U-shaped bracket 99 mounted on the bottom of platform 55. The latch member is generally of L-shape, having an arm 101 extending upwardly from the hooked portion 91 through a slot 103 in platform 55.

A catch 105, pivoted at 107 at the upper end of a bracket 109 mounted upon the platform 55, cooperates with the upper end of the latch arm 101 to hold the latch member 89 in position to lock switch bar 77 in its vertical closed-circuit position (Fig. 4). Catch 105 has a notch 111 on one side of its pivot 107 for receiving the upper end of latch arm 101. The latch member 89 is biased to its released position wherein its hooked portion is raised out of notch 93 in switch bar terminal 87 by means of a spring 113 compressed between a portion 115 of bracket 109 and latch arm 101. The catch 105 is biased toward its position for holding engagement of the upper end of latch arm 101 in notch 111 (clockwise as viewed in Fig. 4) by means of a spring 117. A link 119 is pivotally connected to the catch 105 on the side opposite the notch 111 for rocking the catch to release the latch arm 101. Link 119 is adapted to be pulled down to rock the catch 105 to release latch arm 101 by a step-by-step overload-responsive mechanism generally designated 120 mounted upon platform 55.

As illustrated, the overload-responsive mechanism 120 comprises a current relay or solenoid 121 having a frame 123, a coil 125 and an armature or plunger 127 slidable within the coil. The frame 123 is mounted upon the platform 55 with the coil 125 in horizontal position for horizontal movement of the plunger 127. The plunger ex-

tends out of the end of the coil toward the upper insulator 5 and carries at its outer end a shifter fork 129. Fork 129 engages the vertical arm of a bell crank lever 131 fixed on a rock shaft 133. Shaft 133 is journalled in a bearing lug 135 bent up from an electrically conductive plate 137 fixed on platform 55, and in the vertical legs 139 and 141 of a bracket 143 of inverted U-shape fixed upon the plate 137 (Fig. 3). A tension spring 145 is connected between the end of the horizontal arm of bell crank lever 131 and a lug 147 extending from the frame 123 of solenoid 121 to bias the bell crank counterclockwise as viewed in Fig. 4 to pull the solenoid plunger 127 out from coil 125. Spring 145 is shown completely in Figs. 1 and 3 but fragmentarily in Fig. 4. Outward movement of solenoid plunger 127 under the bias of spring 145 is limited by pin 149 extending upward from platform 55 (Figs. 2 and 3). The arrangement is such that when the coil 125 is energized by an overload current, plunger 127 is retracted into the coil, and shifter fork 129 at the outer end of plunger 127 rocks the vertical arm of bell crank lever 131 toward the solenoid, at the same time tensioning spring 145 so that it may act to pull the plunger out of the coil when the coil is subsequently deenergized.

A pawl arm 151 is rotary on rock shaft 133 next to the vertical arm of bell crank lever 131. The pawl arm is biased in the direction toward the solenoid by a tension spring 153 connected between the upper end of the pawl arm and a lug 138 extending from the solenoid frame 123. A finger 157 extends horizontally from the vertical arm of the bell crank lever 131 for engagement by the pawl arm 151 to control movement of the latter. Finger 157 extends through a notch 159 in pawl arm 151 adjacent its upper end in that side of the pawl arm toward the solenoid. The arrangement is such that finger 157 normally holds pawl arm 151 in a retracted position determined by engagement of the pawl arm with a stop 161 against the bias of spring 153 (Figs. 1 and 4). When the vertical arm of bell crank lever 131 is rocked toward the solenoid upon energization of coil 125, pawl arm 151 is released and rocks toward the solenoid under the tension of spring 153. Stop 161 is conveniently constituted by a finger bent up from the material of plate 137. A pawl 163 is pivoted at 165 on pawl arm 151 for driving an indexing ratchet 167 forward upon rocking of pawl arm 151 in the direction toward the solenoid. A pawl spring 169 biases the pawl 163 toward ratchet 167.

Ratchet 167 is mounted upon a ratchet shaft 171 journalled at one end in a bearing lug bent up from plate 137 and at its other end in an extension 173 of leg 139 of bracket 143. Fixed on ratchet shaft 171 adjacent extension 173 is a holding ratchet 175. A holding pawl 177 is pivoted at 179 for engagement with holding ratchet 175. Pivot 179 is in a bearing lug 180 struck up from a stamping 181 fixed to the top of bracket 143. Stamping 181 is L-shaped in plan (Fig. 2), having a transverse arm 183 extending toward pawl arm 151 for engagement by a depending finger 185 of pawl 163 when the pawl arm is in its retracted position to raise the pawl. Stamping 181 has a longitudinal arm 187 from which the bearing lug 180 extends upward, and is provided at the end of longitudinal arm 187 with a portion 189 bent upward and then transversely to provide a stop for limiting upward movement of holding pawl 177 (Fig. 5). The latter is biased

toward engagement with holding ratchet 175 by a spring 191.

A portion of the plate 137 is bent up as indicated at 193 to provide a mounting for a dashpot type timer 195. Other types of timers may be used. The time 195 shown comprises a cylinder 197 having a closed end fixed to the upper end of mounting 193, the cylinder extending horizontally toward the upper insulator 5. A piston rod 199 extends from a piston 201 in cylinder 197 out of the open end of the cylinder for engagement by a dashpot operating arm 203 fixed at its lower end on rock shaft 133. The piston 201 and piston rod 199 are biased toward the operating arm 203 by a compression spring 205 reacting from the closed end cylinder 197 against the piston.

The cylinder 197 is provided with a check valve 207 adapted freely to permit escape of air from within cylinder 197 when piston 201 is moved toward the closed end of the cylinder, and to check flow of air into the cylinder without entirely preventing such flow, when the piston is moved toward operating arm 203 by spring 205 to retard the return movement of piston 201 and piston rod 199 under the bias of spring 205. On piston rod 199 is a collar 209 for engaging a finger 211 extending upward from holding pawl 177 near the end of the return stroke of the piston. The arrangement is such that as piston rod 199 nears the end of its return stroke, collar 209 engages finger 211 to rock holding pawl 177 out of engagement with holding ratchet 175.

Ratchet shaft 171 has an arm 213 fixed thereon for actuating the catch-operating link 119 through a lost-motion connection (Figs. 4 and 5). As illustrated, this connection is conveniently provided by means of a screw 215 at the outer end of the arm 213 extending through an elongate slot 217 in the link 119. A tension spring 219 is connected between the arm 213 and a finger 221 bent from the material of bracket 143 for biasing the shaft 171 to rock arm 213 upward.

Screws 57 and 59 by means of which the platform 55 is attached to bracket 51 are insulated from plate 137, the latter being suitably recessed and apertured for this purpose. Screw 57 is connected by a wire 223 to one terminal of solenoid coil 123. The other terminal of the coil is connected by a wire 225 to conductive plate 137 at 227.

Plate 137 is in electrically conductive relation with respect to bracket 109, which is made of conductive material. Bracket 109 has lower flanges 229 fixed to platform 55 by screws 231. These screws extend through the platform and hold bracket 99 on the bottom of the platform. They provide for electrical connection from plate 137 through bracket 109 to bracket 99.

A contact member 233 is pivoted at 91 to bracket 99. This contact member is formed with a contact pad portion 235 for engagement by the terminal 87 on the upper end of switch bar 77 when the latter is in its circuit-closing position. When the switch bar is in this position, it holds the contact member 233 against the bias of a compression spring 237 reacting from the end of recess 239 in the bottom of platform 55 against an extension 241 of contact member 233. Contact member 233 carries a pair of spring contacts 243 for engagement with the legs of the bifurcated end portion 53 of bracket 51 when switch bar 77 is in circuit-opening position. A pigtail 245 connects bracket 99 and contact mem-

ber 233. All the parts above platform 51 are enclosed by a protective cover 247.

The circuit breaker 1 of this invention is particularly adapted for use in a branch line of a power distribution system in connection with a main or so-called back-up automatic circuit recloser in the main line of the system for isolating the branch line from the remainder of the system upon occurrence of a permanent fault in the branch line, but not upon occurrence of a temporary fault of short duration in the branch line. For this purpose, circuit breakers 1 are connected in the branch lines of a power distribution system as illustrated in Fig. 6. Main line

15 L leads from substation S of the power distribution system and includes a back-up automatic circuit recloser CR of a usual type. Branch lines B lead from main line L and each includes a circuit breaker 1 of this invention. Each branch line B leads to line wire connector 49 and from line wire connector 67 of the circuit breaker (Figs. 1 and 2).

The automatic circuit recloser CR, as known, is adapted automatically to operate through a predetermined number of cycles in response to occurrence of a fault anywhere in the system, in each of which cycles it opens and recloses the main line L. If the fault has not been corrected by the time the recloser has operated through the predetermined number of cycles, the recloser locks out to open the main line until it is manually reclosed. Such reclosers are well known in this art and need no detailed description.

Each circuit breaker 1 is adapted automatically to disconnect its branch line B from the main line L upon occurrence of a fault in the branch line if the fault has not cleared by the time the recloser has operated through a number of cycles less than the number required to lock out the recloser. As herein illustrated, the circuit breaker 1 is adapted to lock out so as to disconnect the branch line after the third reclosure of recloser CR if the fault in the branch line has not cleared by that time, and the recloser is adapted automatically to reclose at least one more time before locking out, so that the main line is closed after the faulted branch line is isolated from the main line. This maintains service upon the remainder of the system. Each of ratchets 167 and 177 accordingly has (for example) three teeth for three-step operation of the circuit breaker as will be made clear. Other numbers of teeth may be used, provided the number of operations to lock out a branch circuit breaker CB is one less than the operations required to lock out the main circuit recloser CR.

Operation is as follows:

Under normal operating conditions, the switch bar 77 is latched in circuit-closing position by engagement of the hooked portion 91 of the latch member 89 in notch 93 in terminal 87 at the upper end of the switch bar (Fig. 1). The terminal 87 engages the contact pad 235 of contact member 233 and holds contact member 233 against the bias of spring 237 in a position wherein spring contacts 243 are disengaged from the legs of the bifurcated end portion 53 of bracket 51. The branch line circuit is completed through the circuit breaker from the connector 49 through clamp 70 jaw 43 and bracket 51, screw 57, wire 223, solenoid coil 125, wire 225, connection 227, plate 137, bracket 109, screws 231, bracket 99, pigtail 245, contact member 233, terminal 87, switch bar 77, hinge member 73, pigtail 83, and clamp 33 to the line wire connector 67.

The latch hook 91 is retained in latching position in notch 93 in terminal 87 of the switch bar by the engagement of the upper end of latch arm 101 in notch 111 of the catch 105. While line current is flowing through the solenoid coil 125, energization of the solenoid for normal current values is insufficient to draw the solenoid plunger 127 into the coil. Consequently, bell crank lever 131, pawl arm 151, and dashpot operating arm 203 are in their illustrated retracted positions. Rocker arm 213 is in its uppermost position wherein the screw 215 at its outer end extends through the upper end of the elongate slot 217 in the catch-operating link 119 (Fig. 5). Piston rod 199 of the dashpot timer is fully extended by the spring 205 in dashpot cylinder 197.

Assuming that a permanent fault occurs in the branch line B in which the circuit breaker 1 is connected, both branch line B and main line L are overloaded. The resultant overload current in line B energizes solenoid coil 125 sufficiently to attract plunger 127 into the coil. Overload current in main line L causes circuit recloser CR to open the main line L. The recloser, however, does not open the main line until shortly after the solenoid plunger has been attracted into the solenoid coil.

When the solenoid plunger 127 is attracted into the coil, shifter fork 129 at the outer end of the plunger rocks the vertical arm of bell crank lever 131 toward the solenoid. This releases the pawl arm 151 for rocking movement toward the solenoid under the tension of its biasing spring 153. As the pawl arm rocks toward the solenoid, pawl 163 on the pawl arm rocks into engagement with ratchet 167 and indexes this ratchet forward for a distance of one tooth. Since holding ratchet 175 is fixed on ratchet shaft 171 along with ratchet 167, it is also indexed forward for a distance of one tooth. Meanwhile, bell crank lever 131 has rocked the rock shaft 133 to pivot dashpot operating arm 203 toward the dashpot to drive piston rod 199 into the dashpot cylinder 197. The collar 209 thereupon moves away from finger 211 of holding pawl 177, so that pawl 177 rocks into engagement with holding ratchet 175 behind the first tooth thereon to prevent reverse rotation of ratchet 175, ratchet shaft 171 and ratchet 167. Rotation of the ratchets through one tooth rocks the rocker arm 213 on the ratchet shaft 171 downward, but not far enough downward to operate the catch-operating link 119, due to the lost motion provided for by slot 217.

After the above-described operations have occurred, the solenoid plunger 127 is pulled away from the coil 125 by spring 145 acting through bell crank lever 131 and the shifter fork 129, the plunger moving to its normal retracted position against stop pin 149. This occurs upon deenergization of solenoid coil 125 upon opening of the main line L by circuit recloser CR. As the vertical arm of bell crank lever 131 returns to its retracted position, finger 157 thereon pulls pawl arm 151 back to its retracted position thereby tensioning pawl arm spring 153. Ratchets 167 and 177 remain in the position to which they have been advanced by pawl 163, however, due to the holding action of pawl 177 on holding ratchet 175. When the bell crank lever 131 rocks to its retracted position, it rocks the rock shaft 133 to pivot dashpot operating arm 203 back to its retracted position to permit the spring 205 to drive the piston rod 199 out of the dashpot cylinder 197. Return movement of piston rod 199, however, occurs more slowly, due to the slow rate of return

of air into the dashpot cylinder through check valve 207. Consequently, the collar 209 on piston rod 199 delays engagement with finger 211 of holding pawl 177 to release the holding pawl (for example, the delay is of the order of ten seconds).

The recloser CR immediately recloses the main line L. Since the fault in branch line B is a permanent fault, overload current again flows through the branch line and energizes solenoid 121 sufficiently to attract plunger 127 into the coil. Pawl arm 151 is thereupon actuated in the same manner as above described to cause pawl 163 to index ratchet 167 forward through a second step. Holding pawl 177 engages behind the second tooth of holding ratchet 175 to hold both ratchets in advanced position. Rotation of the ratchets through this further step rotates ratchet shaft 171 to rock arm 213 further downward, but still not far enough to actuate the catch-operating link 119. Piston rod 199 meanwhile is slowly moving out of dashpot cylinder 197, but has not moved far enough for collar 209 to engage finger 211 on the holding pawl 177 to release the latter.

The circuit recloser CR then opens for the second time, since the fault in branch B has not been cleared. This opens the main line and de-energizes solenoid coil 125. Bell crank lever 131, pawl arm 151, and dashpot operating arm 213 thereupon return to their retracted positions for the second time.

The circuit recloser CR then again recloses the main line L. Since the fault in branch line B has still not cleared, overload current again flows through the solenoid coil 125. This pulls in the solenoid plunger 127 to rock bell crank lever 131 and release the pawl arm 151 for movement toward the solenoid so that pawl 163 engages the ratchet 167 and drives it forward through a third step. This rocks the arm 213 on ratchet shaft 171 sufficiently for screw 215 to engage the lower end of slot 217 and pull down the catch-operating link 119. This raises the notched end of catch 105 to release the upper end of latch arm 101. Latch member 89 is thereupon biased by spring 113 to its released position wherein its hooked portion 91 is raised out of notch 93 in switch bar terminal 87. This releases the switch bar 77, which swings downward about pivot 75 under the bias of spring 85 until terminal 87 at the upper end of the switch bar engages lug 95. Upon such movement of the switch bar, contact member 233 is released and pivots about pivot 97 under the bias of spring 237 until spring contacts 243 engage the legs of the bifurcated end portion 53 of bracket 51.

With switch bar 77 in its open-circuit position, the branch line D is isolated from the main line L. The circuit recloser CR, however, automatically recloses once more to close the main line L to maintain service on the remainder of the power distribution system. Ultimately, piston rod 199 of the dashpot timer moves to its fully extended position, and collar 209 thereon engages finger 211 of holding pawl 177 to rock the pawl 177 out of engagement with holding ratchet 175. This releases both ratchets, the ratchet shaft 171 and the arm 213 on the ratchet shaft for return to their initial positions under the bias of spring 219. Pawl 163, at this time, is held in raised position above ratchet 167 by engagement of finger 185 of pawl 163 with arm 183, to permit this return movement.

Assuming that the parts are in their initial illustrated positions and that a temporary fault, of momentary duration, occurs in the branch line

B, both the branch line and the main line L are momentarily overloaded. The overload current energizes the solenoid coil 125 sufficiently to attract plunger 127 into the coil. This causes the ratchets 167 and 175 to be stepped forward through one tooth and held in this position by the holding pawl 177 in the manner above described. Rocker arm 213 rotates downward, but not far enough to operate the catch-operating link 119. The dashpot operating arm 203 drives the piston rod 199 into the dashpot cylinder 197.

The solenoid coil 125 is subsequently deenergized when main line L is opened by circuit recloser CR. This permits all the parts to return to their initial positions. Since the fault was of momentary duration, and has now cleared, the solenoid coil is not re-energized sufficiently to attract the plunger, and recloser CR remains closed to complete both the main line L and the branch line B. Piston rod 199 moves slowly out of the dashpot cylinder 197 and ultimately the collar 209 on the rod engages finger 211 of the holding pawl 177 and rocks it away from the holding ratchet 175, to permit spring 219 to return the ratchets 167 and 175 and the rocker arm 213 to their initial retracted positions. This resets the step-by-step pawl and ratchet indexing mechanism for three-step operation for a subsequent permanent fault.

It will be understood that the temporary fault in the branch line may be of such duration as to cause operation of the pawl and ratchet indexing mechanism through two steps without releasing the switch bar 71. Under such circumstances, the solenoid operates twice, and the ratchet mechanism is stepped forward through two teeth, but as long as the fault is cleared before the circuit breaker has had time to operate through the third step, the bar 71 remains in circuit-closing position. The circuit breaker locks out to open the branch line only for faults of such duration as to give the circuit breaker time to operate through three steps, as determined by the speed of the opening and reclosing operations of the back-up circuit recloser CR. As stated above, the number of steps may be varied simply by varying the number of teeth on the ratchets and the extent of lost motion at 215-217. The check valve 207 of the dashpot timer 195 is adjusted so that the collar 209 on the dashpot piston rod will not trip finger 211 to release holding pawl 177 until the circuit breaker has had time to operate through the desired number of steps. To reclose the circuit breaker once it has locked out, it is merely necessary for the lineman to pull down on the hook 81 with a lineman's stick to swing switch bar 71 upward into latched position. This swings latch member 89 so that the upper end of its latch arm 101 catches in the notch 111 in the catch 105.

It will be observed that as soon as the switch bar 71 moves to open-circuit position, spring contacts 243 move into engagement with the legs of the bifurcated end portion 53 of bracket 51. If an arc should be drawn from the contact pad 235 to the terminal 87 of the switch bar, the resultant heavy arcing current will be shunted from the solenoid coil, flowing from bracket 51 through spring contacts 243 to contact pad 235, rather than through screw 57 and wire 223 to the coil. Thus, heavy arcing current is prevented from damaging the coil. If such an arc is sustained, the line becomes grounded or connected to neutral through the arc when terminal 87 engages grounding lug 95. A flexible fiber shield

249 may be provided on the clamp 33, as illustrated in Fig. 1 to prevent flash-over.

An important advantage of the above-described circuit breaker is that the force acting to move the pawl arm 151 and the pawl 163 thereon, to actuate ratchets 167 and 175, is independent of the overload current actuating the solenoid. This is because the bell crank lever 131 actuated by the solenoid functions merely as a detent for holding the pawl arm 151 in retracted position, and is not mechanically coupled to the arm. When the solenoid is energized by overload current and its plunger rocks the bell crank toward the solenoid, the bell crank releases the pawl arm so that the latter is rocked only by its spring 153 for indexing purposes. The force with which pawl arm 151, ratchets 167 and 175, ratchet shaft 171, rocker arm 213, link 119 and catch 105 are actuated depends only upon the bias of spring 153, and not upon the force with which plunger 127 of the solenoid is attracted into the coil 125. Thus, these parts are not affected by the jolt on the bell crank lever 131 when the plunger is attracted into the coil with great force and rapidity by a high overload current, and may be made of relatively small size without being subject to breaking down. At the same time full force of the solenoid action is applied to setting the timing mechanism 195. This is desirable because most of such mechanisms require substantial driving force for setting them. Equivalent timing mechanism might be a spring-biased bellows, an escapement-controlled gear train or the like.

In view of the above, it will be seen that the several objects of the invention are achieved and other advantageous results attained.

As many changes could be made in the above constructions without departing from the scope of the invention, it is intended that all matter contained in the above description or shown in the accompanying drawings shall be interpreted as illustrative and not in a limiting sense.

We claim:

1. A circuit breaker comprising a switch having a movable switch member biased to open-circuit position, a latch for latching the switch member in closed-circuit position against its bias, a current relay operable in response to flow of overload current in the circuit in which the switch is connected, a resettable indexing pawl and ratchet mechanism actuated by said relay and controlling said latch through a linkage including a lost-motion connection to release the latch after a predetermined number of cycles of operation of the relay, said mechanism including a holding pawl for holding it in indexed position, a time-delay mechanism for releasing the holding pawl to reset the indexing mechanism a predetermined time interval after an initial cycle of operation of the relay, and an operating member controlled by the relay for initiating the operation of the time-delay mechanism.

2. A circuit breaker comprising a switch having a movable switch member biased to open-circuit position, a latch for latching the switch member in closed circuit position against its bias, a catch for releasably holding the latch in latching position, an indexing mechanism operable through a predetermined number of steps for releasing the catch, a movable actuating member for the indexing mechanism and biased to actuate the indexing mechanism, a current relay operable in response to flow of overload current in the circuit in which the switch is connected, and a de-

11

tent controlled by the relay for holding said actuating member in a retracted position against its bias, said detent releasing said actuating member upon operation of the relay for movement of the actuating member under its bias to actuate the indexing mechanism through one step.

3. A circuit breaker as set forth in claim 2 wherein the indexing mechanism is biased to an initial position, and further including a releasable holding member for holding the indexing mechanism in its stepped positions, time control mechanism for releasing said holding member a predetermined time interval after an initial operation of the relay, and an operating member controlled by the relay for initiating the operation of the time control mechanism.

4. A circuit breaker comprising a switch having a movable switch member biased to open-circuit position, a latch for latching the switch member in closed-circuit position against its bias, a catch for releasably holding the latch in latching position, a ratchet mechanism biased to an initial position, a linkage including a lost-motion connection between said ratchet mechanism and catch for releasing the catch upon rotation of the ratchet mechanism from its initial position through a predetermined number of steps, a driving pawl for the ratchet mechanism, a current relay operable in response to flow of overload current in the circuit in which the switch is connected, mechanism controlled by the relay to actuate the driving pawl to drive the ratchet mechanism forward through one step upon each operation of the relay, a holding pawl for holding the ratchet mechanism in its stepped positions against its bias, and time-delay mechanism for releasing said holding pawl a predetermined time interval after an initial cycle of operation of the relay to permit return of said ratchet mechanism to its initial position under its bias.

5. A circuit breaker comprising a switch having a movable switch member biased to open-circuit position, a latch for latching the switch member in closed-circuit position against its bias, a resettable step-by-step indexing pawl and ratchet mechanism controlling said latch through a linkage including a lost-motion connection to release the latch upon operation of the indexing mechanism through a predetermined number of steps, said mechanism including a driving pawl normally biased to a retracted position and a holding pawl for holding it in indexed position, a solenoid operable in response to flow of overload current in the circuit in which the switch is connected controlling said driving pawl to release it to operate the indexing mechanism through one step upon each operation of the relay, and time-delay mechanism for releasing the holding pawl

12

to reset the indexing mechanism a predetermined time interval after an initial cycle of operation of the relay.

6. A circuit breaker comprising a switch having a movable switch member biased to open-circuit position, a latch for latching the switch member in closed-circuit position against its bias, a catch for releasably holding the latch in latching position, a ratchet mechanism biased to an initial position, a linkage including a lost-motion connection between said ratchet mechanism and catch for releasing the catch upon rotation of the ratchet mechanism from its initial position through a predetermined number of steps, a rock shaft, a pawl arm rotary on the rock shaft carrying a driving pawl for the ratchet mechanism, a first spring biasing the pawl arm toward the ratchet mechanism for driving the latter through the driving pawl, a detent fixed on the rock shaft for holding the pawl arm in retracted position against the bias of the spring, a second spring coupled to the rock shaft for biasing said detent to position to hold the pawl arm in retracted position, a solenoid coupled to the detent and operable in response to flow of overload current in the circuit in which the switch is connected against the bias of said second spring to actuate the detent to release the pawl arm to drive the ratchet mechanism through one step, and a holding pawl for holding the ratchet mechanism in its stepped positions against the bias of said ratchet mechanism.

7. A circuit breaker as set forth in claim 6, further including a time-delay mechanism for releasing the holding pawl a predetermined time interval after an initial cycle of operation of the solenoid to permit return of the ratchet mechanism to its initial position under its bias, and an operating arm for the time-delay mechanism fixed on said rock shaft.

8. A circuit breaker as set forth in claim 7 wherein the time-delay mechanism comprises a dashpot having a cylinder and piston, a piston rod extending from the cylinder for engagement by the operating arm, and a member on the piston rod for engaging and releasing the holding pawl.
